(57) CLAIM

What is claimed is the ornamental design for a handle for an umbrella, as shown and described.

DESCRIPTION

FIG. 1 is a top, front and right side perspective view of a new design for a handle for an umbrella;

FIG. 2 is a top plan view of the handle for an umbrella shown in FIG. 1; and,

FIG. 3 is a front elevation view of the handle for an umbrella shown in FIG. 1, a side and a rear elevation view thereof being identical.

The dashed lines shown in the figures are for illustrative purposes only and form no part of the claimed design.
